[57] CLAIM

The ornamental design for a toy space vehicle, as shown and described.

DESCRIPTION

FIG. 1 is a perspective view of a toy space vehicle showing our new design; and,

FIG. 2 is a top plan view thereof.

The bottom of the toy space vehicle is plain and unornamented and does not show any part of our ornamental design, which is shown completely in FIGS. 1 and 2.

1 Claim, 2 Drawing Sheets

FIG. 1

FIG. 2
